(57) **CLAIM**

The ornamental design for an air box for a motor vehicle, as shown and described.

DESCRIPTION

FIG. 1 is a top view of an air box for a motor vehicle showing my new design;

FIG. 2 is a left side view thereof;

FIG. 3 is a bottom view thereof;

FIG. 4 is a perspective view thereof;

FIG. 5 is a back view thereof;

FIG. 6 is a front view thereof; and,

FIG. 7 is a right side view thereof.

The broken line shown in the drawings are for the purpose of illustrating portions of the article that form no part of the claimed design.
